UNITED STATES PATENT OFFICE

HARVEY D. GEYER, OF DAYTON, OHIO, ASSIGNOR TO THE INLAND MANUFACTURING COMPANY, OF DAYTON, OHIO, A CORPORATION OF DELAWARE

REFRIGERATOR DOOR OF MOLDED ASPHALT COMPOSITION

Application filed March 9, 1927. Serial No. 174,085.

This invention relates to the construction of heat insulating doors or panels for refrigerator boxes.

An object of this invention is to provide an improved form of refrigerator door or panel for building a refrigerator box which will not corrode or rust in damp climates, which will have good appearance and heat insulating qualities, and which can be rapidly manufactured at small cost.

A more specific object is to provide such a door or panel, the main portion of which is of a molded asphalt composition.

A further object is to provide an improved type of door gasket and means of retaining it in place whereby the gasket may be easily inserted or replaced after a period of use by an unskilled person.

Further objects and advantages of the present invention will be apparent from the following description, reference being had to the accompanying drawings, wherein a preferred form of embodiment of the present invention is clearly shown.

25 In the drawings:

Fig. 1 is a plan view looking down upon Fig. 2 of a refrigerator door built according to this invention.

Fig. 2 is a vertical section on line 2—2 of 30 Fig. 1.

Similar reference characters refer to similar parts throughout the several views.

Referring to the drawings, 10 designates the relatively heavy molded composition 35 door frame and 11 the relatively thin panel which is preferably molded integral with the frame 10. An inner sheet metal lining 12, preferably porcelain coated, lies upon and is secured to the inner surface of the frame 10, thereby forming a complete closure for the interior recess 13 of the molded door. This recess is filled with any suitable heat insulating material 14, such as the loose cork illustrated, or cork board.

40 The inner face of frame 10 has a groove 15 molded therein extending entirely around the periphery of the door. The edge of the metal lining 12 lies adjacent to the groove 15, and an inner moulding strip 16, having a 45 tongue 17 which nests within groove 15, is

applied thereover to firmly clamp the lining in place. This strip 16 is preferably of a molded composition material and may be molded in one piece, that is a single one-piece moulding frame of the proper dimensions to fit the door, as clearly shown in the drawings. The moulding frame 16 is rigidly clamped in place by the screws 18 suitably spaced around the periphery of the door. These screws 18 will cut their own threads in the 55 60 65 70 75 80 85 90 95 100

molded material of frame 10 when driven home with a screw-driver. The deeply countersunk heads of screws 18 are plugged over with a suitable sealing compound 19 so that no metal other than the porcelain coated lining 12 will be exposed on the inside of the door.

If it is desired to have a sealing gasket on the door, a suitable groove 25 is molded, partly in frame 10 and partly in the moulding frame 16, as clearly shown, so as to provide a continuous groove extending around the periphery of the door. A soft rubber gasket 26 is provided having a portion 27 retained snugly within groove 25 and a portion 28 projecting outwardly from the door to engage the rabbeted abutment of the door opening and thereby form a good air seal for the door. It is thus seen that the moulding frame 16 serves the double function of 70 75 80 85 90 95 100

retaining the metal lining 12 and the rubber gasket 26 in place and completely conceals the edges thereof and so forms a neat inner construction.

Preferably the soft rubber gasket 26 is 85 molded in an endless one-piece form of the proper dimensions to fit snugly within the groove 25. This gasket can then be removed by catching hold of the projecting portion 28 and pulling it out of the dovetail groove 25 when it is desired to replace a worn out gasket. The new gasket can be inserted without removing the moulding frame 16 simply by stretching a certain length of the gasket at a time to reduce the cross section of the portion 27 and permit its easy insertion within the groove 25. It is thus seen that after these gaskets deteriorate and become poor seals after a certain period of use they can be 90 95 100

easily replaced by an unskilled owner without calling for the service man.

The composition material from which members 10 and 16 are molded is compounded from gilsonite or other hard asphalt, a suitable flux such as a low melting petroleum residue, disintegrated asbestos fiber, and a suitable inert filler such as kieselguhr, fine clay, or powdered slate. This composition and the processes of mixing and molding the same is fully described and claimed in my copending application, Serial No. 169,669, filed February 19, 1927.

This composition material is well adapted for this use since it is strong, well appearing, heat insulating, non-corroding and non-affected in any way by moisture such as by swelling and warping, and may be rapidly and economically produced by what is termed a cold molding process. The door hinges (not shown) may be easily secured to the relatively strong frame 10 by suitable bolts or large wood screws since screws hold well in this material.

25 While the form of embodiment of the present invention as herein disclosed, constitutes a preferred form, it is to be understood that other forms might be adopted, all coming within the scope of the claims which follow.

30 What is claimed is as follows:

1. As an article of manufacture, a heat insulating door for refrigerator cabinets, comprising: a relatively thick section panel frame and a relatively thin panel integrally 35 molded of a heat insulating bituminous composition comprising hard asphalt, a flux of lower melting point, asbestos fiber (and an inert filler to form an interior recess of substantial depth, an inner metal lining secured to the inner surface of said frame to thereby 40 form a closure for said interior recess, and heat insulating material filling said recess.

2. As an article of manufacture, a heat insulating door for refrigerator cabinets, comprising: a relatively thick section panel frame and a relatively thin panel integrally 45 molded of a heat insulating bituminous composition to form an interior recess of substantial depth, an inner metal lining for said frame forming a closure for said interior recess, a heat insulating bituminous composition moulding overlapping the edge of said lining and secured to said frame, and heat insulating material filling said recess.

55 3. As an article of manufacture, a heat insulating panel for refrigerator cabinets comprising: a heat insulating bituminous composition outer panel having a peripheral frame integrally molded therewith and extending 60 inwardly to form an interior recess, said composition consisting of gilsonite, a flux for said gilsonite, disintegrated asbestos fiber, and a heat, non-conductive inert filler, an inner metal lining overlapping and secured to 65 said frame to form a complete closure for

said interior recess, and heat insulating material filling said recess.

4. As an article of manufacture, a heat insulating door for refrigerator cabinets, comprising: a recessed outer panel molded in one piece from a hot plastic compound of bituminous material, fiber, and inert filler, an interior metal lining fixed to said molded outer panel to close said recess, and heat insulating material filling said recess between 70 said panel and lining.

In testimony whereof I hereto affix my signature.

HARVEY D. GEYER.
